DESIGN FOR A BED LAMP

Bernard A. Mitchell, Chicago, Ill.

Application March 18, 1940, Serial No. 91,015

Term of patent 7 years

To all whom it may concern:

Be it known that I, Bernard A. Mitchell, a citizen of the United States, residing at Chicago, in the county of Cook and State of Illinois, have invented a new, original, and ornamental Design for a Bed Lamp, of which the following is a specification, reference being had to the accompanying drawing, forming part thereof.

Fig. 1 is a perspective view of a bed lamp showing my new design.

Fig. 2 is a front elevational view of same.

Fig. 3 is a side elevational view looking in the direction of line 3—3 of Fig. 1.

Fig. 4 is a plan view looking in the direction of line 4—4 of Fig. 2.

I claim:

The ornamental design for a bed lamp, as shown.

BERNARD A. MITCHELL.
